HONING MACHINE

Albert M. Johnson, Rockford, Ill., assignor to
Barnes Drill Co., Rockford, Ill., a corporation of
Illinois

Application December 30, 1938, Serial No. 248,393

13 Claims. (Cl. 51—34)

The invention relates to machine tools generally, and more particularly to honing or lapping machines.

Machines of the above general character are used extensively in finishing cylindrical work to accurate dimensions and with a smooth, true surface. The finishing operation is effected by relative rotation of a cylindrical abrasive tool and the work, while the supports which carry the tool and work are simultaneously relatively reciprocated to traverse the tool axially of the work. One of the supports is therefore mounted on a suitable guideway for movement toward and from the other support.

Various drive mechanisms have been employed in machines of the above type for reciprocating the movable support. Where relatively long work pieces are involved necessitating a long stroke of the movable support, a drive mechanism of the drum and cable type, such as that disclosed in my prior Patent No. 2,106,216 of January 25, 1938, has been found most satisfactory for this purpose. The mechanism ordinarily comprises a pair of flexible traction members such as cables each connected at one end to the movable support and anchored at the other end to a grooved cable drum rotatably supported at one end of the guideway. One cable leads directly to the drum while the other cable is carried over a sheave journaled at the other end of the guideway. When the cable drum is rotated, first in one direction and then in the other direction, the cables are alternately wound up and paid out so as to pull the movable support back and forth on the guideway.

In order to obtain the smooth shockless reciprocation which is peculiarly essential to precision honing, it is necessary to avoid any slack in the cables of the driving mechanism and preferably to maintain them under tension at all times during the operation of the machine. The problem of maintaining the cables under proper tension is complicated by the fact that the force required to reciprocate the movable support varies within wide limits for different types and sizes of work, and particularly in the case of machines which may be required to remove a substantial amount of material from the work in a minimum of time. With this in view, one object of the invention is to provide improved means for tensioning the drive cables in machines of the above general character so as to enable the machines to operate with a high degree of accuracy under a wide variety of working conditions.

Another object is to provide improved means whereby the tension applied to the drive cables is automatically adjusted in accordance with the force required to reciprocate the movable support.

Another object of the invention is to provide novel means for automatically removing the sludge from the coolant settling tank and for depositing it in a suitable receptacle which can be quickly and easily removed or emptied.

Other objects and advantages of the invention will become apparent from the following description of the preferred embodiment illustrated in the accompanying drawings, in which:

15 Fig. 1 is an elevational view of a honing machine embodying the features of the invention.

Fig. 2 is a plan view of the intermediate section of the machine.

Fig. 3 is a detail view of the improved drive cable tensioning mechanism.

Fig. 4 is a schematic diagram showing the hydraulic circuits and apparatus of the machine.

20 Fig. 5 is a sectional view taken along the line 5—5 of Fig. 2, showing the settling tank cleaning apparatus in end elevation.

Fig. 6 is a detail view showing the drive mechanism for the conveyor chain which forms a part of the settling tank cleaning mechanism.

25 By way of illustration, the invention has been shown and will be described hereinafter as applied to a horizontal honing machine of the type in which the honing tool is rotated and reciprocated relative to a stationary work piece. It is to be understood, however, that the invention is applicable to other types of honing machines and, as to certain phases, it is applicable to machine tool structures generally. It is also to be understood that various changes in the form, construction and arrangement of the parts constituting the invention may be made by those skilled in the art without departing from the spirit and scope of the invention as defined by the appended claims.

30 Referring to Fig. 1, the exemplary machine selected to illustrate the invention comprises generally an elongated base consisting of rectangular sections 7 and 8 bolted or otherwise secured together in end-to-end relation. The base section 7 is provided with a suitable horizontally disposed guideway for a reciprocating head 9 which constitutes a movable support for a generally cylindrical abrasive tool or hone 10. The tool 10 is carried on the projecting end of

an elongated spindle or driver 11 journaled on the head. A motor 12 also mounted on the head 9 serves to rotate the spindle 11 and tool 10.

The base section 8 which, in the present instance, constitutes the work support, is equipped with suitable brackets 13 for supporting work such as a cylindrical tube 14 in axial alinement with the spindle 11 of the tool support. As herein shown, the brackets 13 are adjustably secured to a bed in the form of a plate 15 extending across the base section 8. The plate is provided with the usual longitudinal T-slots 15^a to which the brackets may be bolted. Also mounted on the plate 15 is a coolant fixture 16 adapted to fit over the end of the work piece 14 and arranged to direct a supply of coolant into the same. The necessary coolant is supplied thereto by a motor driven pump 17 which withdraws the coolant from a reservoir 18 in the base section 8 and delivers it through a filter 19 and a flexible tube 20 to the fixture 16.

Means is provided for reciprocating the head 9 on the guideway to traverse the tool axially of the work. In the particular machine illustrated, this means comprises a pair of flexible cables 21 and 22 each anchored at one end to the head and at the other end to a grooved cable drum 23 journaled in a housing 24 mounted on the end of the base section 7 farthest from the work. The cable 21 leads directly to the drum while the cable 22 is carried over a sheave 25 rotatably supported at the opposite end of the base section 7. With this arrangement, rotation of the drum 23 in one direction is effective to wind up the cable 22 and thus pull the head toward the work, while rotation of the drum in the other direction winds up the cable 21 and pulls the head toward retracted position. Any suitable means such as a rotary hydraulic motor 26 (Fig. 4) may be employed for rotating the drum 23 to reciprocate the head.

In order to insure smooth and shockless reciprocation of the head, the cables 21 and 22 must be held relatively taut and without any appreciable slack. Means is therefore provided for placing the cables under tension at all times while the machine is in operation. In the particular form of the invention illustrated, this is accomplished by shifting the position of the sheave 25 as required, and to this end the sheave is supported on a bearing capable of being moved longitudinally of the machine bed so as to vary the distance between the sheave and the cable drum. The movable bearing, as shown in Figs. 1 and 3, is in the form of a generally U-shaped bracket 27 pivoted intermediate its ends on pivot pins 28 carried on spaced vertical webs 29 (Fig. 2) formed integrally with or rigidly secured to the base section 7 adjacent the forward end of the guideway. The sheave 25 is held between the arms of the bracket on a shaft 30 supported on the respective arms. As the axis of the shaft 30 is offset with respect to the pivotal axis of the bracket, movement of the sheave longitudinally of the guideway may be effected by rocking the bracket about its pivot.

Power actuated means is provided for rocking the bracket in a direction to increase the distance between the sheave and the cable drum and thereby apply tension to the cables 21 and 22. The power actuated means in its preferred form is hydraulically operated, and as herein shown comprises a cylinder 31 anchored at its closed end between vertical ribs 32 integral with the

front end wall of the base section 7. Preferably, the connection between the cylinder and the rib is provided by a pin 33 which permits limited pivotal movement of the cylinder for reasons which will appear presently. The cylinder 31 has a working piston 34 connected by a piston rod 35 with one arm of a lever 36 pivoted intermediate its ends on a pin 37 extending between the webs 29 of the base section 7.

10 A rigid link 38 connects the upper end of the lever 36 with the upper end of the bracket 27. As will be seen by reference to Fig. 2, the link 38 is bifurcated at one end to straddle the sheave 25 and at the other end to straddle the upper 15 end of the lever 36. Pins 39 and 40 connect the link with the lever 36 and bracket 27, respectively. Through the connection thus provided by the lever 36 and link 38, the piston 34 is effective upon movement to the right as viewed in Fig. 3, to rock the sheave supporting bracket 27 in a counterclockwise direction and thus move the sheave 25 farther from the cable drum 23. Tension is thus applied directly to the drive cable 22 and, since the head 9 is slidably supported on the guideway, cable 21 is likewise tensioned. The cylinder 31 is enabled to accommodate itself to the lateral movements of the piston in rocking lever 36 by reason of its pivotal support on the base.

15 30 The pull exerted on the cables 21 and 22 varies, of course, in accordance with the direction in which the head is being moved and is dependent upon the resistance encountered by the tool in its rotation and relative reciprocation in engagement with the work. In order to maintain the cables under proper tension at all times, pressure fluid is supplied to the cylinder 31 variably so as to increase the force applied to the sheave supporting bracket when the cable 22 is active in moving the head 9 and to decrease such tension when the cable 21 is functioning for this purpose. Thus, the pull exerted by the cable 22 on the sheave is counterbalanced and the cables are maintained under proper tension for smooth and shockless reciprocation of the head 9.

20 35 Referring more particularly to Fig. 4, the hydraulic circuit for supplying pressure fluid to the cable tensioning cylinder and its relation to the other hydraulic circuits of the machine will be 40 readily apparent. As shown in the drawings, pressure fluid for driving the cable drum driving motor is supplied by a pump 41 driven by a motor 42. The pump withdraws oil or other suitable fluid from a reservoir or sump 43 and delivers it under pressure to a main pressure line 44 from which a series of branch lines extend to the various machine elements and control devices.

25 45 50 55 60 65 70 75 One branch 45 of the main pressure line 44 extends to a reversing valve 46 of the usual and well known construction which is arranged to connect feed lines 47 and 47^a of the hydraulic motor 26 alternately with the pressure line and with a drain or return line 48 leading back to the sump 43. The construction of the valve 46 is such that when its plunger is in the position shown in Fig. 4 pressure fluid is supplied to the motor through the line 47 and spent pressure fluid is exhausted through line 47^a and the drain 48. Under these conditions, the motor rotates in a direction to turn the cable drum 23 counterclockwise (as viewed in Fig. 1) so as to wind up the cable 22 and thus move the head 9 toward the forward end of the guideway. The cable 21

is paid out as the cable 22 is wound up on the drum.

Upon operation of the valve plunger to its alternate position, pressure fluid is supplied to the motor 26 by way of the line 47^a and spent pressure fluid is exhausted through the line 47 and drain 48. Under these conditions, the direction of the motor is reversed and likewise the direction of rotation of the cable drum 23, so that the cable 21 is now wound up on the drum and the head 9 is drawn back to retracted position. The operation of the reversing valve 46 is effected, in the present instance, by pressure fluid supplied through a branch line 49 and under control of a pilot valve 50 operated by the head 9 in well known manner incident to its reciprocation.

In order to avoid the formation of slack in either of the driving cables as the head 9 is moved back and forth on the guideway, the inner end of the cable tensioning cylinder 31 is connected directly to the main pressure line by a branch line 51 so that piston 34 is constantly urged toward the right as viewed in Fig. 4. The other end of the cylinder is connected by a line 53 with the motor feed line 47^a which carries pressure fluid only when the motor is being driven in a direction to wind up the cable 21 and pay out the cable 22.

When the motor 26 is operated to move the head 9 forwardly by winding up the cable 22, the feed line 47^a is connected to the drain as above explained, hence the full pressure of the line 44 is applied to the left end of the piston 34. The piston acting through the rod 35, lever 36 and link 38 thus tends to swing the sheave supporting bracket 27 in a counterclockwise direction against the pull exerted by the cable 22 in drawing the head forwardly. Due to the leverage provided, the pressure applied to the piston is thus enabled to counterbalance the pull of the cable 22 and to take up any slack in the cable 21 as it is paid out by the rotating cable drum. Moreover, it will be apparent that the force exerted on the sheave supporting bracket is proportioned to the force required to move the head forwardly since the pressure in the line 44 will build up in accordance with the resistance offered to the reciprocation of the tool, that is, to the hydraulic rotation of the motor 26.

When the motor 26 is reversed, the cable 21 is wound up to draw the head to retracted position and cable 22 is paid out. The cable 22 therefore does not exert any substantial pull on the sheave 25, hence no counterbalancing force is required. However, it is necessary to maintain sufficient pressure on the left end of the piston 34 so as to take up any slack in the cable 22 as it is paid out from the drum. Application of the required amount of pressure is effected automatically by the introduction of pressure fluid into the right end of the cylinder 31 from the feed line 47^a. Since the piston rod 35 extends through the right end of the cylinder, the active area of the right end of the piston is substantially smaller than the active area of its left end. Accordingly, only the pressure differential is applied to the sheave supporting bracket and in a direction tending to move the sheave to the left as viewed in Fig. 3. Thus the cable tensioning mechanism functions to maintain sufficient tension on the cable 22 to take up any slack that might otherwise appear as the cable is unwound from the cable drum. Further, the tension on the cable is substantially uniform throughout the return stroke of the head.

In the case of horizontal honing machines of

the above general character as well as in other types of honing machines, the pump 17 is arranged to flood the work and tool with a copious supply of liquid coolant such as kerosene, mineral seal oil or the like during the honing operation. This coolant serves both to prevent overheating of the tool and work and to carry away the metal particles removed from the work and the abrasive particles worn from the tool. The coolant must, of course, be perfectly clear and free of grit initially to avoid any chance of scratching or otherwise marring the surface of the work.

For reasons of economy, it is desirable to use the coolant again and again, which necessitates the removal of the solid particles before it is returned to the work. Accordingly, the coolant, after leaving the work with its entrained metal and abrasive particles is caught on the bed plate 15 and drained into a shallow pan 55 (Figs. 1 and 2) set in the machine base at the forward end of the work supporting section 7. An opening 56 in one side of the pan allows the coolant to flow into a settling tank 57 in which the heavier particles of abraded material are permitted to settle out. The coolant then returns to the reservoir 48 through an opening 58 (Fig. 5) in the side wall of the base section 8, which opening communicates with the tank 57 at a point substantially above the bottom thereof.

In large honing machines, and in fact in any honing machine designed for the removal of a relatively large quantity of stock in the honing operation, the abraded material or sludge accumulates so rapidly in the settling tank that frequent shut-downs of the machine may be necessary to permit removal of the accumulated material, or else an attendant must give substantially his whole time to keeping the tank clean. Either is objectionable, since in one case it decreases the operating efficiency of the machine and, in either case, it adds materially to the cost of the honing operation. These difficulties are avoided in the present instance by the provision of a novel conveyer for automatically removing the sludge from the settling tank, the tank being designed with a particular view of accommodating an endless chain conveyer for this purpose.

Referring to Figs. 2 and 5, the settling tank 57 as herein shown is of generally rectangular form and is assembled with the machine as an integral part of the base section 8. One side wall of the tank is formed jointly by a section 59 of the side wall of the machine base and by an outwardly and downwardly inclined side plate 60 welded or otherwise secured along its upper edge to the wall 59. The other side wall of the tank is formed by a vertical plate 61 which merges into an inwardly and downwardly inclined side plate 62. The plates 60 and 62 terminate at their lower edges in substantially vertical portions 60^a and 62^a spaced apart laterally to define a relatively narrow trough-like bottom for the tank. The lower edges of the side plates 60 and 62 are welded or otherwise secured to a bottom plate 63 projecting horizontally from the base section 8, this plate forming the bottom of the tank. Inwardly and downwardly inclined end plates 64 and 65 close the ends of the tank.

The heavier particles of abraded material entrained in the coolant introduced into the tank settle toward the bottom of the tank and are directed into the trough-like bottom portion thereof by the converging side walls 60 and 62. This trough-like bottom of the tank forms a run for a chain conveyer which is arranged to carry

the sludge from the tank and to deposit it in a receptacle such as a drum 66 which can be removed quickly and easily and replaced by an empty drum when full so as to avoid any necessity of shutting down the machine.

The sludge removing conveyer as herein shown is in the form of an endless chain scraper comprising an endless chain 67 to which are secured a series of transverse plates or scrapers 68 (Fig. 6). The chain is supported by sprocket wheels so that the scrapers are drawn along the trough-like bottom of the tank and up the inclined end wall 65 by appropriate movement of the chain. To this end, sprocket wheels 69 and 70 are supported in the tank adjacent the bottom and at opposite ends thereof as shown in Fig. 1. A third sprocket wheel 71 is mounted at the upper end of the tank adjacent the outer edge of the end wall 65, thus providing two angularly related runs of chain extending parallel to the bottom plate 63 and to the end plate 65, respectively.

The sprocket wheel 71 is preferably adjustably supported to permit adjustment of the tension of the scraper chain 67. To this end, the sprocket wheel is keyed to a transverse shaft 72 (Figs. 5 and 6) journaled in bearings formed in spaced depending arms 73 of a slide 74. The slide may be dove-tailed or otherwise slidably secured on an inclined pad 75 formed on a bracket 76 rigid with the base section 8 and projecting laterally therefrom to overlie the settling tank, as shown in Fig. 5. An adjusting screw 77 rotatably anchored to the slide 74 and threaded into a lug 78 rigid with the bracket 76 provides a convenient means of moving the slide as required. The inclination of the pad 75 is preferably the same as that of the end wall 65 so that adjustment of the chain may be made without moving the scrapers 68 out of contact with the end wall of the tank.

Any suitable means may be employed for driving the scraper chain to remove the sludge from the tank. The driving means as herein shown comprises a pawl and ratchet mechanism equipped with a hydraulic actuator arranged to impart step by step rotating movement to the sprocket wheel 71. As shown in Fig. 6, a ratchet wheel 81 is keyed to the shaft 72 which carries the sprocket wheel 71. Loosely mounted on the shaft 72 adjacent the ratchet is a disk 82 on which is pivoted a pawl 83 adapted to coact with the teeth of the ratchet wheel. The arrangement of the pawl is such that when the disk is rocked about the axis of the shaft 72 in a clockwise direction, as viewed in Fig. 6, a similar rotative movement is imparted to the ratchet and the associated sprocket wheel 71. Upon rotation of the disk 82 in the opposite direction, the pawl slides over the teeth of the ratchet without moving the same. If desired, a locking pawl may be provided for preventing reverse movement of the ratchet, although ordinarily this is unnecessary as the friction of the parts is sufficient to perform this function.

The hydraulic actuator for the pawl and ratchet mechanism is arranged to rock the disk 82 periodically to advance the scraper chain step by step. The actuator, as herein shown, comprises a cylinder 84 rigidly mounted on the slide 74 which carries the sprocket and associated equipment so that adjustments of the tension of the sprocket wheel may be made without affecting the drive mechanism. The cylinder 84 is provided with a working piston 85 having a piston rod 86 connected by a link 87 with an arm 88 projecting radially from the disk 82.

A compression spring 89 acting on the piston 85 normally holds it in the upper end of the cylinder. Upon introduction of pressure fluid into the upper end of the cylinder, the piston is forced 5 downwardly against the action of the spring 89, thus rocking the disk 82 in a clockwise direction and, through the medium of the pawl and ratchet mechanism, imparting a rotative step to the shaft 72 and sprocket wheel 71. When the pressure is relieved, the spring 89 returns the piston 85 to its upper position, thereby rocking the disk 82 back to the normal position shown in the drawings.

While the supply of pressure fluid to the scraper chain driving cylinder 84 may be controlled or regulated in any suitable manner, it is preferred to connect the cylinder with the general hydraulic system of the machine in a manner such that the feed movements of the chain are controlled automatically. In the particular machine 15 illustrated, the upper end of the cylinder 84 is connected by a line 90 with the branch line 51 which in turn connects with the main pressure line 44. A line 91 leads from the lower end of the cylinder to the drain 48 and serves to carry off any fluid which may leak around the piston.

With the above arrangement, a pressure impulse is imparted to the piston 85 and the chain is advanced one step in each machine cycle. At the end of the machine cycle, the supply of pressure fluid is cut off from the machine elements by opening a stop valve 92 which returns the fluid directly to the sump. The piston 85 is therefore relieved of pressure, thereby enabling the spring 89 to return it to the upper end of the cylinder in which it remains until the next pressure impulse is received in the succeeding machine cycle.

It will be apparent that a more rapid feed of the chain may be obtained by connecting the cylinder 84 with a different source of pressure fluid as, for example, with the feed line 47 so that a pressure impulse is applied to the piston 85 each time the head 47 is moved forwardly. Other arrangements of the hydraulic circuit will readily suggest themselves to those skilled in the art.

It will be apparent from the foregoing that the invention provides novel and advantageous means for maintaining the drive cables of a horizontal honing machine or the like under proper tension at all times so that the reciprocatory support may be reciprocated smoothly and with complete absence of shock from slack driving cables. Through the medium of a novel hydraulic actuated means, the tension of the drive cables is automatically adjusted in accordance with the resistance offered to the relative movement of the tool and work.

The invention also provides novel means for automatically removing accumulated sludge from the coolant settling tank of a honing machine or other machine tool in which abraded material is carried away from the work by means of a stream of liquid coolant. The mechanism provided for this purpose is simple in construction, reliable in operation and capable of maintaining the settling tank in condition for proper functioning of the machine.

I claim as my invention:

70 1. In a machine tool, in combination a reciprocatory support, a guideway for said support, means for reciprocating said support on the guideway comprising a drum rotatably supported at one end of the guideway, a bracket pivoted 75 at the other end of the guideway, a sheave jour-

naled on said bracket, a cable extending from said support directly to said drum, a second cable extending from said support and over said sheave to the drum, power actuated means for rotating the drum alternately in opposite directions to wind up and pay out said cables and thereby reciprocate said support, a hydraulic cylinder mounted adjacent said other end of the guideway, a piston in said cylinder operatively connected with said sheave supporting bracket, said piston being operative when shifted in one direction to rock the bracket so as to move said sheave away from the cable drum and thereby place said cables under tension, and means for supplying pressure fluid to the cylinder to shift said piston in said one direction.

2. In a machine tool, in combination, a reciprocatory support, a guideway for said support, means for reciprocating said support comprising a drum rotatably supported at one end of the guideway, a sheave journaled at the other end of the guideway, cables extending from said support to said drum, one of said cables being carried over said sheave whereby to move the head toward said other end of the guideway when the cable is wound up on the drum, pressure fluid operated means for rotating said drum to wind up said cable, means for adjustably supporting said sheave including a movable bearing bracket for the sheave, pressure fluid means tending to shift said bracket in a direction opposite to the pull of said cable, and a hydraulic circuit for supplying pressure fluid from a common source to said drum rotating means and said bracket shifting means whereby the force exerted on said bracket is varied in accordance with the force required to move said support.

3. In a machine tool, in combination, a reciprocatory support, a guideway for said support, means for reciprocating said support comprising a drum rotatably supported at one end of the guideway, a sheave journaled at the other end of the guideway, cables extending from said support to said drum, one of said cables being carried over said sheave whereby to move the head toward said other end of the guideway when the cable is wound up on the drum, means for maintaining said cable under tension including a bearing bracket for said sheave movable longitudinally of the guideway, means for exerting sufficient pressure on said bracket to counterbalance the pull exerted by said one cable in moving the support, and means for decreasing the force exerted on said bracket when the support is moved by the other cable.

4. In a machine tool, in combination, a reciprocatory support, a guideway for said support, means for reciprocating said support comprising a drum rotatably supported at one end of the guideway, a sheave journaled at the other end of the guideway, cables extending from said support to said drum, one of said cables being carried over said sheave whereby to move the head toward said other end of the guideway when the cable is wound up on the drum, means for maintaining said cable under tension including means tending to move said sheave in a direction opposite to the pull of said cable, and means for automatically varying the pressure exerted on said sheave in accordance with the force required to move said support.

5. In a machine tool, in combination, a reciprocatory support, a guideway for said support, means for reciprocating said support comprising a drum rotatably supported at one end of the

guideway, a sheave journaled at the other end of the guideway, cables extending from said support to said drum, one of said cables being carried over said sheave whereby to move the head toward said other end of the guideway when the cable is wound up on the drum, a shiftable bearing bracket supporting said sheave, hydraulically operated means acting on said bracket to maintain said cable under tension, and means for varying the pressure exerted on said bearing in accordance with the pull exerted on the cable by said drum.

6. In a machine tool, in combination, a reciprocatory support, a guideway for said support, means for reciprocating said support comprising a drum rotatably supported at one end of the guideway, a sheave journaled at the other end of the guideway, cables extending from said support to said drum, one of said cables being carried over said sheave whereby to move the head toward said other end of the guideway when the cable is wound up on the drum, means for adjustably supporting said sheave including a shiftable bearing bracket for the sheave, and hydraulically operated means for shifting said bracket to apply a predetermined tension to said one cable.

7. In a machine tool, in combination, a reciprocatory support, a guideway for said support, means for reciprocating said support on the guideway comprising a drum rotatably supported adjacent one end of the guideway, a sheave rotatably supported adjacent the other end of the guideway, flexible cables connecting said support and said drum, one of said cables extending directly to the drum and the other of said cables extending over said sheave and then to the drum, power actuated means for rotating said drum alternately in opposite directions to reciprocate said support, and means for taking up the slack in said cables including hydraulically operated means tending to move said sheave away from said drum.

8. In a machine tool, in combination, a reciprocatory support, a guideway for said support, means for reciprocating said support on the guideway comprising a drum rotatably supported adjacent one end of the guideway, a member rotatably supported adjacent the other end of the guideway, flexible traction members connecting said support and said drum, one of said traction members extending directly to the drum and the other of said traction members extending over said rotatable member and then to the drum, power actuated means for rotating said drum alternately in opposite directions to reciprocate said support, and means for automatically varying the tension of said traction members in accordance with the force required to rotate said drum.

9. In a machine tool, in combination, a reciprocatory support, a guideway for said support, means for reciprocating said support on the guideway comprising a drum rotatably supported adjacent one end of the guideway, a sheave rotatably supported adjacent the other end of the guideway, flexible cables connecting said support and said drum, one of said cables extending directly to the drum and the other of said cables extending over said sheave and then to the drum, power actuated means for rotating said drum alternately in opposite directions to reciprocate said support, and hydraulically operated means for maintaining said cables under predetermined tension.

10. A horizontal honing machine having, in combination, a horizontally disposed guideway, a support mounted for reciprocation on said guideway, a pair of flexible traction members secured to said support and extending in opposite directions therefrom generally parallel to said guideway, pressure fluid operated means acting through said members alternately to reciprocate the support on said guideway, and pressure fluid actuated means operating automatically to maintain the traction members under predetermined tension.

11. A horizontal honing machine having, in combination, a guideway, a support mounted for reciprocation on said guideway, a pair of flexible traction members secured to said support and extending therefrom in opposite directions, a power driven actuator acting through said members alternately to reciprocate the support on said guideway, and means for automatically varying the tension of the traction members in accordance with the force required to move the support.

12. A honing machine having, in combination, a reciprocatory support, a pair of flexible traction

members secured to said support and extending therefrom in opposite directions, a pressure fluid operated actuator acting through said members alternately to reciprocate the support, pressure fluid operated means for applying tension to said traction members, and a pressure fluid circuit for supplying pressure fluid from a common source to said actuator and said tension applying means so that the tension applied to the traction members is determined in accordance with the force required to move the support.

13. A honing machine having, in combination, an elongated base, a support mounted for reciprocation on the base, power driven support reciprocating mechanism disposed within said base, a rotatable member at each end of the base, a pair of flexible cables connected to said support and extending therefrom over said rotatable members respectively and to said mechanism to operatively connect the mechanism with the support, and means for automatically taking up slack in said cables comprising a pressure fluid operated device acting on one of the cables.

ALBERT M. JOHNSON.
